PEDAL FOR VELOCIPEDES

Harry Golden, New York, N.Y., assignor to Ideas for
Auto & Bike Specialties, Inc., New York, N.Y., a cor-
poration of New York

Filed Nov. 29, 1963, Ser. No. 77,605

Term of patent 3½ years

(Cl. D90—14)

FIGURE 1 is a top plan view of a pedal for velocipedes embodying my new design;

FIGURE 2 is an outer end elevation thereof;

FIGURE 3 is a side elevational view thereof; and

FIGURE 4 is a perspective view of the pedal viewed from the inner end thereof.

I claim:

The ornamental design for a pedal for velocipedes, as shown.
